SHADE ROLLER BRACKET

Harry F. Jeffs, Detroit, Mich.

Application July 21, 1944, Serial No. 545,972

1 Claim. (Cl. 248—268)

The present invention relates to new and useful improvements in window shade roller brackets, and has for its primary object to provide, in a manner as hereinafter set forth, a device of this character which is adapted to be expeditiously and firmly secured in position on the window frame without the use of nails, tacks, screws, et cetera.

Another very important object of the invention is to provide a shade roller bracket of the aforementioned character which may be readily installed and removed several times without marring the woodwork.

Other objects of the invention are to provide a shade roller bracket of the character set forth which will be comparatively simple in construction, strong, durable, compact, neat and attractive in appearance and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a view in front elevation, showing a pair of brackets in accordance with the present invention in use.

Figure 2 is a view in horizontal section, taken substantially on the line 2—2 of Figure 1.

Figure 3 is an elevational view of the bracket which receives the stationary shade roller spindle.

Figure 4 is an elevational view of the bracket which receives the rotating shade roller spindle.

Referring now to the drawing in detail, it will be seen that the embodiment of the invention which has been illustrated comprises a horizontally elongated base 1 of suitable dimensions and material, said base being of substantially the shape shown to advantage in Figures 3 and 4 of the drawing. Formed integrally with the end portions of the base 1 are substantially triangular horizontal prongs or teeth 2. The teeth 2 are adapted to be driven into the opposed sides 3 of the window frame for mounting a pair of the brackets thereon.

Formed integrally with the base 1 on an intermediate portion thereof is a substantially U-shaped horizontal loop 4. One of the loops 4 of the brackets comprising a pair has formed there-

in a vertically elongated opening 5 for the reception of the usual stationary spindle 6 on one end of a shade roller 7. An entrance opening or slot 8 communicates with the opening 5 for engaging the stationary spindle 6 therein from the top thereof. The loop 4 of the other bracket of the pair has formed therein a circular opening 9. The opening 9 accommodates the usual rotating spindle 10 on the other end of the shade roller 7.

It is thought that the manner in which the bracket functions will be readily apparent from a consideration of the foregoing. Briefly, the bracket may be readily installed by tapping the end portions of the base 1 in a manner to cause the prongs 2 to bite into the woodwork. The loop 4 provides a convenient handle for holding the bracket while the prongs 2 are thus being driven into the woodwork. The construction and arrangement is such as to prevent splitting of the woodwork. Of course, the brackets are installed in pairs on the opposed sides of a window frame. To remove the brackets, it is only necessary to insert a suitable prying instrument under the end portions of the bases 1. It will thus be seen that a shade roller bracket has been provided which may be readily installed without the use of nails, screws, et cetera.

It is believed that the many advantages of a shade roller bracket constructed in accordance with the present invention will be readily understood, and although a preferred embodiment of the device is as illustrated and described, it is to be understood that changes in the details of construction may be resorted to which will fall within the scope of the invention as claimed.

What is claimed is:

A shade roller bracket, comprising a rigid, oblong, base plate, substantially triangular prongs formed on one side of said base plate adjacent its ends and in the plane of its longitudinal center, and a closed, substantially rectangular, transversely opening, loop formed on the opposite side of said base plate midway between its ends, said loop having its open ends disposed in line with longer side edges of said base plate and its bight provided with an opening to be engaged by a spindle of a shade roller, the portions of the base plate at each side of said loop providing impact surfaces to facilitate the driving of the prongs into the framing of a window.
